TUNING CIRCUITS

Carel Jan van Loon, Eindhoven, Netherlands, assignor, by mesne assignments, to Radio Corporation of America, New York, N. Y., a corporation of Delaware

Application October 15, 1937, Serial No. 169,100
In Germany November 2, 1936

7 Claims. (Cl. 250—20)

The invention relates to a circuit arrangement for facilitating the tuning of a radio-receiving apparatus by means of a device which operates when the receiver is correctly tuned. Such devices are particularly important in superheterodyne receiving apparatus with which it is often difficult to tune in such manner that the intermediate frequency is located approximately in the middle of the pass-band of the intermediate-frequency portion. The tuning facilitation may consist, for example, in that, when correct tuning is attained a braking device is put into operation with the result that further movement of the tuning knob is made difficult, or there may be provided an optical indicating device. A further possibility consists in that the low frequency amplifying portion is only made operative, for example, by means of a relay when the receiver is correctly tuned.

Such a tuning-facilitating device must, of course, be preceded by selective controlling means comprising, for example, tuning circuits, which means ensure that the device can only operate in a comparatively narrow band of frequencies. It has previously been proposed to rectify the output voltage of these selective means so that a direct current voltage is obtained which was utilized for controlling the tuning facilitating device, the circuit arrangement being such that the width of the band of frequencies within which said control voltage occurred, was substantially independent of the signal amplitude.

According to the invention, the control of the said device is effected by an auxiliary alternating voltage of comparatively low frequency which is combined with the high- or intermediate-frequency signals in such manner that it can only have effect in a comparatively narrow band of frequencies in the neighborhood of the correct tuning, an extremely simple and reliable control being thus obtained.

A further advantage is that for the amplification of the control voltage use may be made of an alternating current amplifier. As appears from the following it is possible to utilize as such the amplifiers intended for the amplification of the signal voltages. The auxiliary alternating voltage should preferably be taken from the power mains.

The invention is illustrated in the accompanying drawing, wherein Fig. 1 is a block diagram of a circuit embodying one form of the invention, Fig. 2 discloses a modified form of circuit shown in greater detail, and Fig. 3 shows a modifica-

tion of a portion of the circuit shown in Fig. 2.

Referring now to Figure 1 the block 1 denotes a high-frequency amplifier, 2 a local oscillator and 3 an intermediate-frequency amplifier. The intermediate-frequency oscillations amplified are demodulated in a device 4. The low-frequency oscillations produced are supplied, if desired after further amplification, to a load 5, as for example, a loudspeaker.

For the actuation of the tuning facilitating device is used a side-channel which is connected at a suitable point to the intermediate-frequency amplifier. The use of such a side-channel for controlling purposes is known in itself. With the known circuit arrangements the oscillations are led through a selective device which only passes a very narrow band of frequencies; the output energy is rectified and controls a relay by which the brake, or the optical indicating device, is operated.

According to the invention, the intermediate-frequency oscillations are modulated in a device 6 with an auxiliary alternating voltage which may be taken, for example, through a transformer 7 from the power mains. The oscillations thus modulated are subsequently passed through a selective device 8 which transmits a narrow band of frequencies, whereupon the energy transmitted is demodulated in 9 and, if desired, is further amplified. Into the output circuit may be connected an alternating current relay 10 which is consequently put into operation when correct tuning is obtained. It is of course possible to rectify the energizing current for the relay, in which event use may be made of a direct current relay. The relay may be formed as a brake or may actuate a braking device. There is further required a device for the purpose of bringing the relay again in the out of service position when one wants to tune to another station. It is not necessary to utilize a side-channel having particular tubes, but it is also possible to utilize for the purpose described the amplifying tubes which are present already. The control voltage may be introduced into the high-frequency portion 1, or the intermediate-frequency amplifier 3. In this case it is necessary, or at least desirable, to cause this voltage to disappear again after correct tuning has been attained.

A circuit arrangement wherein particular amplifying tubes are not required is shown in Fig. 2 which is more detailed than Fig. 1. The tube 13 in Fig. 2 is assumed to serve for the amplification of the intermediate-frequency oscillations set up

across an input circuit 11. The output circuit 12 of the tube forms, jointly with a circuit 14 with which it is inductively coupled, a band filter tuned to the intermediate frequency. A circuit 19 which is, also tuned to the intermediate frequency and which preferably is of excellent quality, is coupled with the circuit 14 by means of a condenser 15. The voltage across the two circuits 14 and 19 are rectified by diode rectifiers 16 and 21 respectively. The circuit of the rectifier 16 comprises resistances 17 and 18. The resistance 18 forms at the same time part of the circuit of the rectifier 21 which comprises, in addition, a resistance 20 and part of a resistance 39, which is connected in the cathode supply lead of a tube 25. On the resistance 17 is a slidable tap which is connected to a contact of a change-over device. This device comprises a switch 23 which occupies, when there is no tuning, the position shown, so that the upper end of the resistance 20 is connected through a resistance and a condenser 24 to the grid of the first low-frequency amplifier.

In the other position of the switch the tap on the resistance 17 is connected to the said grid through the condenser 24. There is provided, furthermore, another low-frequency amplifying tube 26 the anode circuit of which includes an output transformer 27 whose secondary winding supplies a loudspeaker 28. In the position shown, that is to say when there is no tuning, the loudspeaker is disconnected, however, from the secondary winding by a switch 29 and the relay 30 is connected to said winding. The relay 30 may be formed as a brake which acts, when correct tuning is attained, on a brake disc 32 with the result that further turning of a tuning knob 31 is made difficult. In the lead connecting the circuit 11 to earth are included a switch 31 and a source of voltage 33 which furnishes a voltage of low frequency, e. g., of 50 cycles per second. The output circuit further comprises a switch 33 by means of which the relay 30 may be changed over to the secondary winding of a transformer 40. The primary winding of this transformer is connected to the alternating current supply. The relay 30 is formed as an alternating current relay. The switches 22, 23, 29, 33 and 37 are mutually coupled as indicated by the dot and dash lines. When the brake responds they are simultaneously actuated.

The circuit arrangement shown acts as follows: When there is no tuning, all the switches occupy the positions shown. The circuits 14 and 19 and also the attendant rectifiers 16 and 21 with the resistances 17, 18 and 20 serve to limit the control of the relay 30 to a narrow band of frequencies. The nearer to tuning one comes on turning the knob 31, the more the amplitude of the voltage set up across the circuit 14 increases. Even when there is no tuning, direct current voltages are consequently set up across the resistances 17 and 18 by reason of the normal voltage drop in the cathode resistor 39 of the tube 25. The voltage across the resistance 18 is operative in the circuit of the rectifier 21, that is to say in such a sense that a negative bias is applied to the anode. Only at correct tuning when the voltage across the circuit 19 due to the signal acquires a comparatively high value in excess of the negative bias applied to the anode of the rectifier 21 can consequent rectification take place. Consequently only when correct tuning is attained is there set up a direct current voltage across the resistance 20. The constant negative bias which is brought about by the upper part of the resist-

ance 39 has for its purpose to prevent rectification in the rectifier 21 when the variable bias voltage across the resistance 18 still has a small value.

Owing to the presence of the source of voltage 33 the intermediate-frequency oscillations are modulated with a frequency of 50 cycles per second. However, when there is no tuning this frequency cannot reach the grid of the tube 25 since in this case a voltage is not yet set up across the resistance 20. An alternating voltage component of 50 cycles per second does not occur across the resistance 20 until the circuit 19 rectifies, that is to say until correct tuning is obtained. This component is amplified by the low-frequency amplifying tubes 25 and 26, and causes the relay 30 included in the output circuit to respond with the result that any further rotation of the knob 31 is prevented.

At the same time the relay actuates the switches 22, 23, 29, 33 and 37 so that, after tuning has been effected, they are placed in the other switch position. Simple consideration shows that the apparatus is now suited to normal broadcast reception. The diode 16 acts now as a detector, the low-frequency signal voltages are taken from the resistance 17, and supplied through the condenser 24 to the grid of the first low-frequency tube 25. Since the switch 22 is closed, the rectified voltage of the circuit 19 can no longer act on that of the circuit 14. The source of voltage 33 is switched out of circuit so that the auxiliary voltage is caused to disappear, but the relay remains in the operating position owing to the switch 33 being shifted to the lower contact in which case the relay 30 is maintained energized through the transformer 40 connected to the A. C. supply.

If it is desired to tune to another station, the relay has to be set again out of operation. To that end the tuning knob may be associated with a switch device which is actuated, for example by a longitudinal motion of the knob or by rotation of the latter through a determined angle, for example, against the action of a spring.

It is not necessary that the introduction of the additional alternating voltage should be effected by modulating the intermediate or high-frequency signals with this voltage and by demodulating them afterwards again. Another possibility consists in that the source of additional voltage is operative in the circuit of the rectifier 21. Also in this case an alternating voltage component having a frequency of 50 cycles per second cannot be set up across the resistance before the diode 21 rectifies, that is to say before correct tuning is obtained. This possibility is shown in Fig. 3. According to this mode of realization the source of voltage 33 is located between the anode of the rectifier 21 and the circuit 19. It may be adapted to be switched out of circuit, but this is not necessary under all conditions.

What I claim is:

1. A system for determining accurate tuning of a radio receiver comprising a braking device operatively related to the tuning mechanism of the receiver and preventing further adjustment of the tuning mechanism when in accurately tuned position, a relay for actuating the braking device, a locally produced auxiliary source of low frequency voltage superimposed on the receiver circuit for energizing the relay, and means included in said circuit for blocking transmission of said auxiliary voltage to the relay except

when the receiver is in accurately tuned condition.

2. A system for determining accurate tuning of a radio receiver comprising a braking device operatively related to the tuning mechanism of the receiver and adapted to prevent further adjustment of the tuning mechanism when in accurately tuned position, a relay for actuating the braking device, a locally produced auxiliary 10 source of low frequency voltage superimposed on the receiver circuit for energizing the relay, and circuit means permitting transmission of said auxiliary voltage to the relay only when the receiver is in accurately tuned condition.

15 3. A system as defined in claim 2 wherein the brake actuating relay operates to disconnect the auxiliary source of voltage upon accurate tuning adjustment of the receiver.

4. The combination with a radio receiver having a high frequency portion, a signal detector and a low frequency portion, of means for facilitating accurate tuning of the receiver, said means comprising a braking device operatively related to the tuning mechanism of the receiver and 20 adapted to prevent further adjustment of the tuning mechanism when in accurately tuned position, a relay associated with the low frequency portion of the receiver for actuating the braking device, a locally produced auxiliary source of 25 low frequency voltage superimposed on the high frequency portion of the receiver for energizing the relay, and means associated with the signal detector for blocking transmission of said auxiliary voltage to the relay except when the receiver is in accurately tuned condition.

30 5. The combination with a radio receiver having a high frequency portion, a signal detector, a low frequency portion and a sound reproducer, of means for facilitating accurate tuning of the 40 receiver and preventing further adjustment of the receiver tuning mechanism when in accurate tuning position, comprising a braking device operatively related to the tuning mechanism a relay associated with the low frequency portion of the 45 receiver for actuating the braking device, an auxiliary source of low frequency voltage super-

imposed on the high frequency portion of the receiver for energizing the relay, circuit means operating in conjunction with the signal detector permitting transmission of said auxiliary voltage to the relay only when the tuned circuits of the receiver are so adjusted to pass a comparatively narrow band of frequencies in the neighborhood of correct tuning, and means controlled by the relay in its operative condition to disconnect the auxiliary source of voltage and to connect the signal detector directly to the low frequency portion of the receiver.

5 6. In a receiving circuit, a signal channel comprising a high frequency amplifier portion, a detector and a low frequency amplifier portion, 15 means for adjusting the tuning of the receiver, a brake member associated with said tuning means and operative only when the receiving circuit is in accurately tuned condition, and means for controlling the operation of said brake member 20 comprising a locally produced source of low frequency voltage, and circuit means associated with the detector for preventing the transmission of the low frequency voltage when the receiving circuit is substantially off tune.

25 7. In a receiving circuit, a signal channel comprising a high frequency amplifier portion, a signal detector and a low frequency amplifier portion, means for adjusting the tuning of the receiver, a brake member associated with said tuning 30 means and operative only when the receiving circuit is adjusted to pass a comparatively narrow band of frequencies in the neighborhood of correct tuning, means for controlling the operation of said brake member comprising a source 35 of low frequency voltage which is impressed on the signal channel, circuit means associated with the signal detector for preventing the transmission of the low frequency voltage except only when the receiving circuit is in substantially correct tuning adjustment, and means controlled by the relay after the correct tuning adjustment has been made for disconnecting the auxiliary source of voltage and also the circuit means associated with the signal detector.

40 45 CAREL JAN VAN LOON.
